CLAIM

The ornamental design for a LED package, substantially as shown and described.

DESCRIPTION

FIG. 1 is a front perspective view of the LED package.

FIG. 2 is a top plan view of the LED package of FIG. 1.

FIG. 3 is a lower side view of the LED package of FIG. 1.

FIG. 4 is a right side view of the LED package of FIG. 1.

FIG. 5 is a bottom plan view of the LED package of FIG. 1, wherein the broken lines are shown for illustrative purposes only and forms no part of the claimed design.

FIG. 6 is an upper side view of the LED package of FIG. 1; and,

FIG. 7 is a left side view of the LED package of FIG. 1.
